COLLAPSIBLE TUBE COATING MACHINE

George W. Temple, Flushing, N. Y., assignor to
Victor Metal Products Corporation, Brooklyn,
N. Y., a corporation of New York

Application April 24, 1942, Serial No. 440,276

3 Claims. (Cl. 91—44)

This invention relates to machines for coating the interior surfaces of collapsible tubes and particularly to the means for depositing a layer of wax upon said surfaces.

Machines heretofore known for coating the interior surface of collapsible tubes are comparatively complicated and expensive being designed for automatic operation, and functioning to feed, coat and dry the tube, and then remove it from the machine automatically, as shown for example in my copending application for patent for Collapsible tube spraying machine, Serial No. 405,734, filed August 7, 1941.

In view of present difficulties in obtaining the material and labor necessary for building such machines, the present invention contemplates the provision of a simple and economical machine using few parts for coating the tubes at comparatively high speed with the aid of an operator who manipulates the tubes manually to operate the machine.

The invention further contemplates the provision of a simple device for delivering liquid coating material in sufficient quantity and rapidity against the interior surface of a collapsible tube to coat the tube rapidly and efficiently, said device using a minimum number of special parts and hence being inexpensive and little likely to get out of order.

The invention further contemplates the provision of a simple device permitting the operator to use both hands to insert two collapsible tubes in position in the device simultaneously and to control the discharge of coating material against the inside of the tubes by pressure on the tubes.

The various objects of the invention will be clear from the description which follows and from the drawings, in which,

Fig. 1 is a combined front view and partial vertical section taken on the line 3—3 of Fig. 2 of the coating mechanism showing in dotted lines a position assumed by the pumping and wax delivering mechanism during the swinging movement of said mechanism into or out of the tank of wax.

Fig. 2 is a top plan view of the coating mechanism.

Fig. 3 is a horizontal section of the wax control valve taken on the line 6—6 of Fig. 4.

Fig. 4 is an enlarged front view and partial vertical section of the combined tube support and valve controlling the delivery of wax.

Fig. 5 is a horizontal section of the wax delivery member and tube support taken on the line 5—5 of Fig. 4.

As above indicated, the machine generally comprises a pair of adjacent supports, one for each of the tubes to be coated, together with means for delivering liquid wax or other coating material under pressure into the interior of the tube, thereby to coat the tube. The delivery means for the coating material comprises a pump forcing liquid wax through a control valve into a delivery pipe on which the tube is mounted and a suitably insulated and heated tank for maintaining the coating material in liquid condition.

In the practical embodiment of the invention shown by way of example, the outer container 10 may rest on the floor or on a suitable stand, 15 and is insulated by means of the suitable heat insulation 11 from the intermediate container 12 forming the outer wall of the water compartment 13. The innermost wax container 14 forms the inner wall of the water compartment and is adapted to hold and to conduct heat to the liquid wax 15. Water is supplied to the water jacket by any suitable means such as the funnel 16 and the pipe 17 (Fig. 2), which passes through the containers 10 and 12 and communicates with the water compartment 13. In order to heat the water to the proper temperature, an electric heater 18 of any suitable type is arranged in the water compartment 13 and is supplied with current by the conductor 19 leading to any suitable current source, suitable controls of any well known type not shown, being used if desired to maintain the temperature constant. It will therefore be seen that the water in the compartment 13 may be heated to the desired temperature to maintain the wax in a molten condition during the operation of the machine.

Means are provided for delivering wax to the interior of the work, which is a collapsible tube open at its larger end, in sufficient quantities completely to coat the entire inner surface thereof. As shown, said means comprises the pump 20 of any suitable type from which is suspended the intake pipe 21 which extends downwardly into the tank 14 and to a point quite near the bottom thereof and is connected to the intake side of the pump. On the discharge side of the pump is suspended the pipe 21 connected to the spaced branches 22 and 23 leading to the combined valve and tube supports 24 and 25 respectively, which supports will be described in more detail hereinafter. For operating the pump, the pump shaft 26 is driven by the motor 27 to force liquid wax out of the tank 14 and into the pipes 22 and 23 ready for discharge out of the delivery pipes forming the upper parts of the

members 24 and 25 when the valves are opened.

The entire wax delivering mechanism is mounted for swinging movement to permit the removal of the various pipes 31, 21, 22 and 23 together with the supports 24 and 25 as a unit from the tank when the tank is to be replenished or cleaned as shown by the dash dot lines and by the arrows of Fig. 3. For this purpose, the motor and pump mechanism is mounted on a suitable base or supporting plate 28 connected by the hinge 29 to the fixed support 30.

Referring now to Figs. 3, 4 and 5 for the detailed showing of the combined tube supports and valves 24 and 25, a description of one will suffice for both since both are identical in construction. The branch pipe as 22 is threaded into the lower end of the relatively fixed valve sleeve 32, in the upper end of which is slidably mounted the combined valve member and wax delivery pipe 33. If desired, the spring 34 may be arranged between the lower end of the member 33 and the upper end of the pipe 22, a suitable washer as 35 being interposed between said pipe and the lower end of the spring. The spring aids in maintaining the movable conical valve 36 forming the lower part of the member 33 against the correspondingly shaped fixed valve seat 37 of the member 32, though the wax pressure generated by the pump 20 may be sufficient for this purpose without the aid of the spring.

The elongated passage 38 in the pipe and valve member 33 terminates at its lower end at a point above the valve. To provide communication between the sleeve 32 and the passage 38 in the member 33, a series of radial holes as 39, 40, 41 and 42 (Fig. 3) are provided in the wall of said member just above the valve. Said holes communicate with the space 43 in the sleeve 32 above the valve seat 37 and consequently in the open position of the valve communicate with the space below the valve and with the pipe 22. On depression of the valve 36 in the direction of the arrow 44, wax forced through the pipe 22 enters the space 43, then passes through the holes into the passage 38 and is discharged through the upper end of the member 33 as shown by the arrows at the upper part of Fig. 4. Said member 33 is reduced in diameter at the upper part thereof to form the delivery pipe 45 which is of sufficient length to enter the collapsible tube 46 and to reach a point in slightly spaced relation to the upper end of said tube when said tube rests on the support 48.

Between the pipe portion 45 and the remainder of the member 33 is provided a shoulder 47 on which rests the hub of the conical tube support 48, which is fixed to and movable with the pipe 45. Suitable grooves as 49 are provided in the surface of the support 48, whereby excess or overflow wax delivered into the interior of the tube or discharged from the delivery pipe may return to the tank 14. The pipes 45 are arranged in the upper part of the tank and above the highest wax level for this purpose.

It will be seen that the tube 46 may be quickly mounted on the support 48 to surround the pipe 45 and that a comparatively slight pressure on the tube moves the support 48 downwardly and consequently moves the entire member 33 including the valve downwardly sufficiently to remove the valve from its seat and to permit the liquid

wax to be discharged with great rapidity and in considerable quantity through the upper end of the pipe 45. The wax impinges against the upper end part of the tube and against the tube shoulder and flows downwardly along the tube surface thereby completely coating the tube interior with a layer of the required thickness depending upon the degree of liquidity of the wax and the desired pressure built up by the pump 20. Excess wax drips through the grooves 49 back into the tank.

It will be noted that by reason of the provision of two pipes 45 mounted on the wax supply members 22 and 23 and the spacing of such pipes apart a distance convenient to the operator, the operator may readily grasp two tubes at a time from a source of supply of such tubes, insert them on the supports 48 simultaneously, and simultaneously press down on the supports to open the valves and thus to coat the inner surfaces of both tubes simultaneously. The tubes may then be removed by the operator from the pipes 45.

It will be seen that I have provided a simple, inexpensive but efficient means for supplying liquid under pressure with which to coat collapsible tubes rapidly, which machine is easily operated by unskilled labor and attains adequately the purposes of the invention.

I claim:

1. In a machine for coating the interior surface of collapsible tubes, a heated container for coating material, a pump inlet pipe, a pump carrying said pipe, a discharge pipe carried by the pump, a valve in said discharge pipe, a relatively movable delivery pipe extending from the valve and operating the valve on the movement thereof, and means for pivotally supporting the pump, the valve and said pipes for swinging movement of said pipes into and out of said container.

2. In a machine for coating the interior surface of collapsible tubes, a container for coating material open at its top, a water jacket surrounding the container, a heater in said jacket, a pair of reciprocatory upright delivery pipes each of small enough diameter respectively to enter one of a pair of collapsible tubes, a tube support on each pipe, means for delivering coating material under pressure from the container to said pipes, said means comprising a pump, an inlet pipe suspended from the pump and entering the container, a discharge pipe carried by the pump and connected to said delivery pipes, a valve interposed between said discharge pipe and each of the delivery pipes, and means for swingably supporting the pump, the valves and said pipes for movement of said pipes and valves into and out of the container.

3. In a machine for coating the interior surface of collapsible tubes, a tube support having a conical upper surface provided with drain grooves therein, a vertically reciprocable pipe upstanding from and of lesser diameter than the support, a liquid outlet pipe slidably supporting the reciprocable pipe, a valve interposed between the pipes, means supporting the pipes for forcing liquid coating material therethrough, and a hinged support for the supporting and liquid forcing means whereby said means, the pipes, valve and tube support are swingable as a unit into and out of an operative position thereof.

GEORGE W. TEMPLE.
